SIGNALING SYSTEM

Harold J. Graham, Boston, Mass., assignor, by
mesne assignments, to Signaling Systems In-
corporated, Winthrop, Mass., a corporation of
Massachusetts

Application December 9, 1937, Serial No. 178,941

15 Claims. (Cl. 172—358)

My invention relates to signaling systems, particularly but not exclusively to those in which a signal is given at a station in response to a condition at any one of a plurality of remote stations, such a system being exemplified, for example, by a fire alarm system for a ship or the like in which the existence of a fire in any particular one of a number of staterooms is signaled at the bridge, or any other convenient station on the ship, by use of a bell which taps the number of the stateroom at such station.

The invention will be best understood from the following description when read in the light of the accompanying drawings, the scope of the invention being more particularly pointed out in the appended claims.

In the drawings—

Fig. 1 is a schematic diagram of an alarm system according to the invention;

Fig. 2 is a plan of a selective switch and associated mechanism employed in the system according to Fig. 1;

Fig. 3 is an elevation of the parts shown by Fig. 2;

Fig. 4 is a section on the line 4—4 of Fig. 2 on an enlarged scale, with parts omitted, parts broken away, and parts moved to a different position;

Fig. 5 is a plan of the parts illustrated by Fig. 4; and

Fig. 6 illustrates a detail.

Referring to the drawings, the alarm system comprises a panel 11, indicated by dotted lines in Fig. 1, which panel is located, for example, at the bridge of the ship and supports a single stroke bell 13 for tapping off the numbers of staterooms or other places on the ship when a fire or other condition to be signalled occurs at any one of such places. For causing the bell to be actuated there is located in each of these places a thermostatically or otherwise controlled device 15 which responds to heat or other condition to cause the bell to be operated.

As illustrated in Fig. 1, for controlling the bell circuit there is provided a switch having a spring contact arm 17 and a cooperating spring contact arm 19. By reference to Fig. 1 it will be observed that when the contact arm 17 is moved into contact with the arm 19 there will be established across the battery 21, if the battery switch 23 is closed, which it normally is, a circuit through the winding of the relay 25 by way of the leads 27, 29, 31, 33, 35 and 37. This circuit being established, the armature 39 of the relay will be drawn downward against the tension of

the spring 41 to close the relay switch 43, and that switch being closed will establish a circuit through the bell 13 from the battery by way of the leads 21, 45, 47, 35 and 37. When the relay 25 is deenergized by opening of the switch 17, 5 19 the spring 41 will open the switch 43 to interrupt the circuit through the bell 13. This bell is of the so-called "single stroke" type, that is to say, when energized the bell sounds a single stroke, instead of ringing continuously. Therefore it will be observed that by causing the switch 17, 19 successively to open and close in definite timed relation between each opening and closing thereof the bell 13 may be caused to tap off numbers or other signals. It will of course be understood by those skilled in the art that other signaling means, for example, a lamp caused to flash by opening and closing of the switch afforded by the contacts 17 and 19, may be substituted for the bell 13, or the bell and such a 20 lamp may be arranged in parallel across the leads 35 and 47 so that they will operate simultaneously.

Referring to Fig. 1, the switch 17, 19, as will hereinafter be more fully explained, is caused 25 to be opened and closed by a rotary member 49 driven by an electric motor 51, the rotary member being mounted on a slowly rotating shaft 53 driven by the motor. This rotary member 49 is shown as provided with a series of pins 30 or other projections 55, 57, 59, which pins, as shown by Fig. 4, are arranged in different planes respectively. Each device 15 when operated causes selective switch elements 61 (Figs. 2 and 3), one of which is indicated schematically in 35 Fig. 1, to be arranged in the planes of the respective pins in the space between the rotary member 49 and the switch 17, 19. When the motor 51 is placed in operation to rotate the member 49, the pin in the plane of a member 61, 40 which latter as shown in Fig. 1 has five teeth 63, will successively engage those teeth, and when it engages them will push the member 61 downward, as viewed in Fig. 1, to contact with the switch arm 17 and move it into contact with 45 the switch arm 19, the member 61, as herein-after will be more fully explained, moving away from the switch arm 17 to cause the switch to open each time the pin enters the recesses between the teeth. Thus in this instance the bell 50 13 will be caused to tap off five strokes. By placing three members 61 one above the other each in the plane of one of the pins 55, 57, 59 respectively, as shown by Fig. 4, and providing each member 61 so placed with a different number 55

- of teeth, as shown by Figs. 2, 3 and 5, the bell will be caused to tap off a number consisting of three units, as, for example, the number 541. As hereinafter will be more fully explained, each device 15 causes a different arrangement of the members 61 interposed between the rotary member 49 and switch arm 17 so that when any particular device 15 is operated the bell will tap off a particular number to indicate the stateroom 10 or other place where the device 15 is situated.
- The motor 51, which drives the rotary member 49, is shown as controlled by a switch having the cooperating spring contact arms 65 and 67 which, in a manner hereinafter more fully explained, are caused to be closed when any of the devices 15 cause a plurality of the members 61 to be arranged in juxtaposition to the rotary member 49 for operating the bell. As shown in Fig. 1, one side of the motor is connected to one terminal of the battery 21 by the lead 37, while the other side of the motor is connected by the lead 69 to the switch arm 65, the cooperating switch arm 67 being connected by the lead 27 to the opposite terminal of the battery. Hence when the switch afforded by the arms 65 and 67 is closed, the motor will be placed in operation to rotate the member 49 and cause the bell 13 to sound the alarm.
- With the arrangement just described, when the switch 65, 67 is opened by moving the members 61 out of juxtaposition to the rotary member 49, for causing a secession of the sounding of the alarm, the motor would stop operating in the absence of something to prevent it. For the purpose of causing the motor, when the motor switch 65, 67 is opened, to continue to operate until the member 49 places the teeth 55, 57, 59 in predetermined positions relative to that switch, the shaft 53, as shown by Fig. 1, carries a rotary disk 71 of conductive material having at its periphery an insert 73 of insulating material, a brush 75 cooperating with the periphery of the disk and its insert and being connected by the lead 77 to the lead 27, which latter leads from one terminal of the battery to the switch arm 67 of the motor switch. As schematically illustrated in Fig. 1, the hub portion 79 of the disk 71 is contacted by a brush 81 which is connected by a lead 83 to the lead 69 connecting one terminal of the motor to the other spring arm 65 of the motor switch. It will be noted that with this arrangement the disk 71 is placed in parallel to the motor switch 65, 67. Hence if the motor switch is opened when the brush 75 is off the non-conductive insert 73 the motor will continue to operate until the brush 75 contacts with the insert 73, and this will cause the motor to stop when the rotary member 49 is in a predetermined position.
- Referring particularly to Figs. 2 to 6 of the drawings, the motor 51, as shown, is mounted on the panel 11, the motor driving the vertical shaft 53, above referred to, through suitable reduction gearing, not illustrated, contained in a casing 85 carried by the motor casing, so that the shaft 53 will be rotated at a slow speed say, for example, three or four revolutions per minute. This shaft 53, as heretofore explained, carries the rotary metallic disk 71 having the insert 73 of non-conductive material, the disk being integrally formed with a hub portion 87 secured to the shaft 53 by one or more set screws 89. The brush 75 heretofore referred to is carried by a metallic arm 91 supported by the panel 11 in insulated relation thereto, the end of which arm

is recessed at 93, as shown in Fig. 4, for receiving the brush, a compression spring 95 at the bottom of the recess serving to press the brush outwardly into contact with the periphery of the disk 71.

It will be observed that the disk 71 is in electrical communication with the shaft 53, which latter in practice is in electrical communication with the gear casing 85. Therefore in practice this circumstance may be taken advantage of by insulating the motor casing from the panel and by grounding to this casing that terminal of the motor to which the lead 69 of Fig. 1 is connected. In other words, the brush 81, shown schematically in Fig. 1 for convenience in illustration, may be entirely omitted by this expedient.

As illustrated in Fig. 4, the upper end of the shaft 53 is reduced in diameter at 97 to form an annular shoulder 99. This reduced portion of the shaft 53 receives the hub 101 of the rotary member 49, the hub at its lower end resting upon the shoulder 99 and being secured to the shaft in adjusted rotative positions relative thereto by means of a nut 103 screw-threaded on the end 25 of the shaft. As shown, the skirt 105 of the rotary member 49 is provided with the projecting pins 55, 57 and 59 heretofore referred to, the pins being spaced circumferentially of the rotary member and each pin being in a different 30 horizontal plane from the other.

As illustrated, the brush holding arm 91 has slidably and rotatably mounted thereon a block 107 of insulating material which is fixedly secured in adjusted positions to the arm by a set 35 screw 109. This block carries the two switches formed by the pairs of contact arms 65, 67 and 17, 19 respectively. The construction of these switches is best illustrated in Fig. 4, both switches being alike. As shown, each switch comprises a pair of base portions 111 and 113 insulated from each other and to which the leads may be connected. The spring arm 67 and like spring arm 19 each comprise an elongated flexible metallic member carried at its lower end by the upper 40 end of the base portion 111. The arm 65 and like arm 17 each comprise an upper rigid metallic part connected to the base portion 113 by a flexible metallic spring 115 which normally 45 tends to hold the switch in open position.

As indicated in Fig. 4, the members 61 hereinbefore referred to are dropped in different combinations into the space between the rotary member 49 and the upper rigid portions of the two switches just referred to. The upper rigid portion of the switch 65, 67 for controlling the motor carries a projecting portion 117 of insulating material, so shaped that when three members 61 are piled one on the other on the upper surface of the block 107 the upper member 61 of the pile will contact with the projection 117. Dropping the upper member 61 on the pile pushes the member 117 to the right, as viewed in Fig. 4, and holds the switch 65, 67 permanently in closed position to energize the motor 51 for causing the 60 member 49 to rotate, the latter continuing to rotate until the upper member 61 is moved from the space between the rotary member and projection 117 to permit the motor switch 65, 67 to open and subsequently until the brush 75 rides 70 on the insert of insulating material on the member 71, as has hereinbefore been explained.

As illustrated, the upper portion 65 of the switch 17, 19 for sounding the bell 13 carries a lateral projection 119, of insulating material, 75

which is shaped to be contacted by each of the members 61 when they are moved to the right, as viewed in Fig. 4. As the member 49 rotates, the pins 59, 57, 55 successively engage the teeth of the respective members 61, and, as each pin rides over the teeth of one of the members 61, that member is moved successively to contact the member 119 to move the latter and cause it successively to open and close the switch 17, 19. Fig. 5 illustrates the position of parts when the switch 17, 19 for operating the bell is in closed position. It will be noted that here the pin 59 is in contact with the apex of one of the teeth 63 on the upper member 61, and has pushed that member to the right to contact with the projection 119 on the switch arm 17 to move that arm into contact with the arm 19. When the pin moves farther in its travel it will enter the adjacent recess between the teeth 63, and the upper member 61 will then, through a spring action hereinafter explained, which urges it to the left as viewed in Fig. 5, move to the left out of contact with the projection 119 and permit the switch 17, 19 to open. When the upper member 61 is moved to the right, as viewed in Figs. 4 and 5, to close the switch 17, 19 the projection 117 carried by the switch arm 65 of the motor switch also moves to the right, this movement being permitted by the flexibility of the spring arm 67, which arm will follow the motion of the arm 65 and thus keep the switch 65, 67 closed and cause the motor to continue to rotate.

In this way as the pins successively ride over the teeth of the members 61 a number consisting of three digits (or less, if one or more of the members 61 is left blank in respect to teeth 63) is tapped by the bell 13. The value of each digit depends upon the number of teeth on the member 61, and the value of the number tapped by the bell depends upon the order in which the members 61 are placed on top of the block 107. As illustrated, the parts are arranged for piling three members 61 on top of the block 107, but it will be understood that a greater or lesser number of these may be piled there provided the projection 117 for closing the motor switch is operated by the last member 61 placed on the pile and the projection 119 is arranged to be contacted by all the members that may be in the pile.

Referring particularly to Figs. 1, 2 and 5, it will be observed that six members 61 are herein illustrated, these members being provided with one, two, three, four, five and six teeth respectively. Each member 61 is carried at the end of a spring arm 121, the other end of which arm is rigidly carried by a block 123 swingingly mounted by a horizontal pivot 125 on a bearing block 127 carried by a bracket 129. Two such brackets are shown, arranged at opposite sides respectively of the rotary member 49, the brackets being carried by the panel 11. Extending upwardly from each block 123 is a rod 131 the upper end of which carries an armature 133 cooperating with the pole piece 135 of an electro-magnet 137. When the magnets 137 are energized to attract the armatures 133 the members 61 will be held in their full line positions illustrated by Figs. 2 and 3. By deenergizing any of the magnets its associated member 61 will be permitted to drop into its dotted line position, shown at the right of Fig. 3, between the projections 117 and 119 and rotary member 49 for operating the switches 65, 67 and 17, 19 respectively, as has been hereinbefore explained.

As illustrated, the arms 121 are so bent, and the

blocks 127 are so positioned, that the members 61 will drop into proper juxtaposition with the rotary member 49 upon de-energization of the electro-magnets, the mounting of the members 61 and their movement in this respect being similar to those of the keys of a typewriter. It will therefore be observed that by deenergizing three selected magnets in proper sequence, any combination comprising three different digits of the digits 1 to 6 inclusive may be caused to be tapped off by the bell 13. Obviously a greater or lesser number of members 61 could be provided, as hereinbefore explained.

After an alarm has been sounded, and while it is being sounded, the members 61 may be again placed in their elevated positions in any convenient manner, and will be held there by reason of current caused to flow through the windings of the magnets 137, which is the normal condition of the apparatus. For raising the arms 61 each bracket 129 is shown as provided with a shaft 139 which extends through the panel 11 to the back thereof. This shaft carries a number of fingers 141 positioned beneath the respective arms 121. Normally these fingers will be in their full line positions indicated in Fig. 3, but by turning the shafts 139 the fingers may be raised to their dotted line positions shown at the left-hand side of that figure so as to engage the arms 121 and raise the members 61 and thus bring the armatures 133 into juxtaposition to the pole pieces of the magnets.

As illustrated in Figs. 2 and 6, each shaft 139 rigidly carries behind the panel 11 an arm 143, these arms extending in opposite directions relative to each other and being pivotally connected at their outer ends to a link 145, the link being urged by a spring 147, one end of which is connected to the link and the opposite end thereof to the panel, in such direction as will normally hold the fingers 141 in their lowermost positions. When the fingers are to be raised the link 145 may be moved by the operator to the right, as viewed in Fig. 6, to raise the fingers 141.

It will be observed that as hereinbefore described the armatures 133 associated with the elements 61 of the selective switch device are held in their uppermost positions on account of current normally flowing through the windings of these magnets. However, as will be obvious to those skilled in the art, each armature may be held in upper position by means of a latch which disengages when the current flows through the associated magnet winding, under which condition the magnets would be normally deenergized.

The windings of the magnets 137 for holding the elements 61 in their raised positions are indicated by the same reference character 137 in the schematic wiring diagram illustrated by Fig. 1. One terminal of these magnets as shown is connected by a common lead 149 to the lead 37 from one terminal of the battery 21. The other terminal of each of these magnets as shown is connected by a lead 151 to the movable contact 153 of a relay switch 155, the cooperating contacts 157 of all the relay switches being connected by a common lead 159 to the lead 27 which is connected to the opposite terminal of the battery 21. When the switch 23 is closed, which is the normal condition of operation of the apparatus, the armatures 161 of all the relay switches will be drawn downward from the position of parts illustrated by Fig. 1 against the resistance of the tension springs 163 to close the switches 153, 157. When the current through the winding of any 75

of these relay switches 155 is interrupted, the associated spring 163 will cause the switch 153, 157 to move into open position and therefore interrupt the flow of current through the associated magnet 137, thereby causing the selective switch element 61 controlled by that magnet to drop.

For energizing the windings of the relay switches 155 a tapped resistance, comprising the series connected resistance sections 165, is shown 10 as connected across the opposite battery leads 27 and 37 through a resistance 167 and the winding of a relay 169 respectively, the resistance 167 preferably having the same value as the winding 169, and this value being low as, for example, in 15 the order of 1 ohm so that approximately the entire voltage of the battery 21 will be impressed upon the tapped resistance.

The windings of the middle pair of relay switches 155 as shown are bridged in series across 20 the center resistance section 165, and the extreme right and left hand windings in series across the entire series of resistance sections, while the next to the left hand and next to the right hand windings as shown are bridged in series across the 25 three center resistance sections.

Preferably, but not necessarily, each resistance section 165 has the same ohmic value, as likewise have all the windings 155. By inserting suitable resistances 171 in series with these windings the 30 same potential drop across each winding may be had. Assume, for example, that each resistance section has an ohmic value of 20 ohms and that there are employed five of these sections, and that there are impressed across the entire series of 35 these resistances 25 volts. In such case the drop across each of the two center windings will be 2½ volts. If each winding 155 has a resistance of, for example, 1500 ohms, by making the two resistances 171 associated with the right and left 40 hand windings have a value of 6000 ohms, the voltage drop across these last mentioned windings will be also 2½ volts because there are impressed upon this system of windings and resistances 25 volts. Similarly, if the two resistances associated 45 with the next to the right and next to the left hand windings have a value of 3000 ohms, the drop across these windings will be 2½ volts because there are impressed upon the system including these windings and resistances 15 volts.

50 As shown, a lead 173 at one end thereof is connected to the electrical center of three series of windings 155 bridged across taps on the resistance having the five sections 165. This connection of the three series of windings does not affect 55 the electrical conditions because the points of connection of the lead 173 thereto are at the same potential, namely, that potential which exists at the electrical center of the middle resistance section 165. In practice the wiring may be much 60 simplified by causing the upper terminals of the winding of the relays 155, or the lower terminals of the resistances 171 when the latter are employed, to be connected directly to the lead 173, instead of having the connections as schematically illustrated in Fig. 1.

65 It will be observed that as heretofore described an even number of relays 155 is employed. If an odd number of relays is to be employed one of them may be connected in series with an equivalent resistance so as in effect to provide an even number of relays so far as the resistances of the relays are concerned.

70 The lead 173 extends from wiring on the panel 11 to all the devices 15 severally situated in different staterooms or at different stations on the

ship. Also leading to these devices are a pair of leads 175 and 177 connected to opposite terminals of the battery through the winding of the relay 169 and the resistance 167 respectively. It will be noted that there are only three conductors 5 leading from the panel 11 to the devices 15. These conductors may exist as a three wire cable, across two wires of which the devices 15 are connected in parallel, and may be several hundred feet long so as to include a large number of staterooms. In this way, the complexity of wiring which has rendered prior proposed systems of this sort impractical is entirely avoided.

As illustrated, each device 15 comprises a bimetallic thermostatic switch element 179 about 15 which is wrapped a flexible tapped heating resistance 181, the resistance having six taps, herein numbered 1 to 6, each corresponding to the tap of same number on the series of resistances 165.

As shown, the bi-metallic element of the upper 20 device 15 in Fig. 1 carries at its upper end in insulated relation thereto a switch contact arm 183 connected to the tap 1 of the resistance, while the lower tap 6 of the resistance is connected by an appropriate lead and a normally closed manually operated switch 185 to the lead 175 from one side of the battery. Cooperating with the switch contact arm 183 is a flexible switch contact arm 187, which latter is connected to the lead 177 from the opposite terminal of the battery. If a fire occurs in proximity to this upper device 15 the thermostatic element will flex to the left and move the switch contact arm 183 into contact with the flexible switch contact arm 187, and, the switch 185 being normally closed, that will 35 establish a circuit through the resistance 181 and further heat the bi-metallic element to cause it to flex farther to the left, the arm 187 bending during this continued flexure. At its upper end the bi-metallic arm carries at opposite sides 40 thereof in insulated relation thereto a pair of contacts 189 and 191 which together with the upper end of the bi-metallic element are adapted to wipe over a cooperating switch arm 193 connected to the lead 173 leading to the electrical center 45 of the system of windings of the relays 155 bridged across the series of resistance sections 165. It will be noted that continued flexure of the bi-metallic element will move these three contacts to the left of the contact afforded by 50 the switch arm 193 so that each of the three contacts will be only momentarily connected to the lead 173. This enables the system to be in condition for operation by successively actuated devices 15, it being observed that the members 61 55 of the selective switch are dropped only when the lead 173 is connected to a tap on a resistance 181, as will be hereinafter more fully explained. The manual switch 185, shown at the upper device 15 in Fig. 1, may be provided for all said devices and may be opened manually to disconnect the associated resistance 181 from the battery lead 175 under untoward conditions, say, if a fire occurring at the station where the device 15 is situated should fuse its parts. Obviously, however, a fusible plug may be substituted for the switch 185, and if desired the switch may be entirely omitted as indicated in the other devices 60 65 15.

The bi-metallic element 179 and the two contacts 189 and 191 are adapted to be connected by different flexible leads 195 to selected taps on the resistance 181. For example, as shown in the upper device 15, the tap 2 is connected to the contact 189, the tap 4 to the bi-metallic ele- 70 75 75

ment 179, and the tap 3 to the contact 191, for the purpose of causing the bell 13, when a fire occurs at the station having the upper device 15, to tap off the number 243. By connecting the 5 leads 195 to different taps, as shown in the other devices 15 schematically illustrated, different numbers may be sounded when this device is actuated. Each device 15 employed preferably has the taps differently connected so that each device 10 will cause a different number to be tapped off by the bell.

It will be noted that the same voltage is impressed across the terminals of the resistance 181 as across those of the series of resistance 15 sections 165, and that when one of the contacts 189 and 191 and the contact afforded by the upper end of the thermostatic element 179 contact with the switch arm 193 the potential of the tap on the resistance 181 to which the contact is connected will be impressed upon the lead 173. The resistance 183 divides the voltage in the same way as does the series of resistances 165, as heretofore explained. Therefore, whenever a contact of the thermostatic element 25 contacts with the switch element 193 there will be across the winding of one of the relays 155 zero voltage or some predetermined voltage, depending upon the way the resistance 181 divides the voltage with relation to the way the series 30 of resistances 165 divide it. For example, if the voltage is divided in the same way by these, and the contacts on the resistance 181 are connected as shown at the upper device 15 of Fig. 1, then when the contact 189 contacts with the 35 switch arm 191 the lead 173 will be connected to tap 2 on the resistance 181, which is at the same potential as the tap 2 on the series of resistances 165. Consequently the winding of the relay 155 connected to tap 2 on the series 40 of resistances 165 will have impressed across it zero voltage, and that relay thus will be de-energized to cause the associated switch 153, 157 to open and deenergize the winding of the associated magnet 137 to cause the selective switch element 61 controlled by that magnet to drop. 45 Similarly, when the end of the thermostatic element contacts with the switch arm 193, the element 61 controlled by the relay 155 connected to the tap 4 on the series of resistances 165 will drop, while when the contact 191 contacts with the switch arm 193 the element 61 controlled by the relay 155 connected to the tap 3 will be caused to drop.

The middle device 15, shown in Fig. 1, is exactly like that just described, except that the resistance 181 is caused to be connected across the leads 175 and 177 by means of a switch 197 held in open position by an explodable glass bulb 199. In case of fire the bulb will explode and permit the upper switch arm 201 of the switch 60 197 to move downward and contact with the lower contact shown as associated therewith.

The lower device 15, shown in Fig. 1, in the above respects is exactly similar to the upper one, except that a separate thermostatic switch 65 is provided for connecting the resistance 181 across the leads 173 and 177. This thermostatic switch comprises a bi-metallic element 203 connected to one end of the resistance 181 and cooperates with the contact 205 connected to the battery lead 177. In case of fire the element 70 203 will flex to close the switch, of which it constitutes one element, and thus cause the winding 181 to be energized. As will be obvious to those skilled in the art, both the switch 203 and the switch 197 heretofore described may be

arranged in parallel so that each may control the energization of the resistance 181 in case of fire.

If desired, the resistance 181 can be caused to be energized by conditions other than those 5 of heat as, for example, a switch controlled by fluid pressure in a sprinkler system may be employed, such a switch, for example, comprising a Bourdon tube 207 electrically connected to the upper end of the resistance 181 and having a contact 209 against which the tube moves when the pressure in the sprinkler system to which the Bourdon tube is connected drops to a predetermined value. As will be obvious, the fluid pressure switch may be used alone or in conjunction 15 with any of the heat sensitive switches hereinbefore mentioned for causing energization of the resistance 181.

In operation, when the battery switch 23 is closed, the tapped series of resistances 165 will 20 be connected across the battery terminals, the tap 1 being connected to the right hand battery terminal through the balancing resistance 167 and lead 27, and the tap 6 being connected to the left hand battery terminal through the 25 lead 175, relay winding 169 and lead 37. As the relay windings 155 are connected in pairs across taps on the series of resistances 165, current flows through those windings and causes the armatures 161 to be drawn down to close the switches 153, 30 157. When these switches are closed each of the windings 137 is placed in circuit across the battery because its upper terminal is connected to a lead 149 connected to the left hand battery lead 37 and its lower terminal is connected 35 to the associated switch arm 153, which latter under these conditions contacts with the switch contact 151 connected to a lead 159 connected to the right hand battery lead 27. The energization of the windings 137 in this manner causes the spring arms 121 to be held in their raised 40 positions when moved to the same, in which positions each will stay until its associated winding is deenergized to permit the spring arm to drop as hereinbefore explained.

When a fire heats the upper thermostat shown 45 at the right of Fig. 1, for example, flexure of the thermostatic element 179 closes the switch contacts 183, 187, and that, assuming the switch 185 is closed, connects the associated resistance 181 across the battery in parallel with the series of resistances 165, because the lead 175, which is connected through the switch 185 to the lower terminal 6 of the resistance 181, connects with the tap 6 of the series of resistances 165, while the lead 177, which is connected to the switch contact 187 and hence under these conditions to the tap 1 of the resistance 181, connects with the tap 1 of the series of resistances 165. The flow of current through the resistance 181 causes continued flexure of the element 179 and causes the contact 189, the contact afforded by the upper end of the element 179, and the contact 191 successively to wipe over the contact portion of the switch arm 193 as 60 65 hereinbefore explained.

As the switch arm 193 is connected to the lead 173, one end of which lead is connected to the electrical mid point of each pair of windings 155 connected in series across taps on the series of resistances 165, and the resistance 181 is in 70 parallel with that series of resistances and preferably divided the same way, there will be impressed on that mid point, when the contact 189, which is connected to the tap 2 on the resistance 181, is wiping over the switch arm 75

193, a voltage which is the same as that of the tap 2 on the series of resistances 165. In consequence, under such conditions, there will be momentarily zero voltage across that relay winding 155 which is connected to the tap 2 of the series of resistances 165 when the contact 189 is wiping across the contact portion of the switch arm 191 and that relay winding will momentarily be deenergized to cause the associated switch 153, 157 to open momentarily so as to cause momentary deenergization of the associated winding 137 controlled by that switch. When the winding 137 is deenergized the spring arm 121 controlled by it is caused to drop. Similarly, the switches 153, 157, controlled by the windings 155 connected to the taps 6 and 3 of the series of resistances 165, are caused momentarily to open as the upper end of the thermostatic element 179 and the contact 191, respectively, successively wipe over the contact portion of the switch arm 191. This will set the alarm to tap off the number 263 in this example when the motor 51 is set in operation, because the members 61 having 2, 6 and 3 teeth 63 are placed in the order mentioned in position to operate the alarm controlling circuit.

The circuit heretofore described lends itself admirably to supervision required by the fire underwriters' rules. For example, the remote end 30 of the two leads 175 and 177 may be bridged by a resistance 211 of high value, which will cause a feeble current to flow through those leads at all times and hence through the winding of the relay 169. Should either of these leads be broken, 35 or should the battery 21 become weak, or the normally closed manually operated switch 23 be opened, the circuit through the relay 169 will be interrupted or fall to such a low value as to permit the tension spring 213 acting upon the 40 armature 215 of the relay 169 to raise that armature and close the normally open switch 217. Closure of this switch will establish a circuit through the "continuously ringing" bell 219 and battery 221 so as to sound an alarm.

45 This bell 219 may also be sounded if any of the leads 173, 175 and 177 leading to the thermostatic or other devices 15 become grounded. To this end the mid point of the battery 21 may be grounded as indicated at 223, as likewise may 50 be the lead 225 running to the lower terminal of the winding 227 of a relay switch 229, the other terminal of this winding being connected to the mid point on the series of resistances 165 so that normally no current flows through the winding. 55 When an accidental ground occurs in any of the leads 173, 175 and 177 a circuit will thus be established through the winding 227 and cause the normally open switch 229 to close against the resistance of the spring 231, which switch 60 when closed establishes a circuit through the battery 221 and bell 219.

It will be understood that wide deviations may be made from the forms of the invention herein described without departing from the spirit of 65 the invention.

I claim:

1. In a signaling system, a plurality of potentiometer devices at different stations responsive to conditions thereat to be signaled, a central 70 station, an indicating code signal device at said central station, conductors common to all of said plurality of potentiometer devices and the central station, means at each potentiometer device actuated by the condition to be signaled 75 for successively contacting selected points of

the potentiometer to a certain one of said conductors, and means at the central station responsive respectively to the points of the potentiometer which are contacted for setting up respective code indicia of said signal device. 5

2. In a signaling system, a plurality of potentiometer devices at different stations responsive to conditions thereat to be signaled, a central station, an indicating code signal device at said central station, conductors common to all of said 10 plurality of potentiometer devices and the central station, means at each potentiometer device actuated by the condition to be signaled for successively contacting selected points of the potentiometer to a certain one of said conductors, means at the central station responsive respectively to the points of the potentiometer which are contacted for setting up respective code indicia of said signal device, and means at the central station operating automatically upon 15 the setting up of said code indicia for repeatedly 20 indicating the code indicia set up. 20

3. In a signaling system, a plurality of potentiometer devices at different stations responsive to conditions thereat to be signaled, a central 25 station, an indicating code signal device at said central station, conductors common to all of said plurality of potentiometer devices and the central station, voltage divider means, means including a pair of said conductors and a switch at 30 each of said first mentioned stations responsive to the condition thereat to be signaled for connecting the potentiometer at the station in parallel with a source of electromotive force and said voltage divider means, means at each potentiometer device, actuated by the condition thereat to be signaled, for successively connecting selected points of the potentiometer to another of said conductors, means responsive to a predetermined difference between potentials established by said voltage divider means and those impressed on said last mentioned conductor by the points of the potentiometer successively connected thereto for successively setting up respective code indicia of said signal device. 35

4. A signaling apparatus comprising a plurality of devices at different stations responsive to the conditions to be signaled, a central station, three conductors common to all said devices and central station, a pair of said conductors being connected to the opposite terminals of a source of electromotive force, each device comprising a tapped resistance and means responsive to the condition thereat to be signaled for bridging said resistance across said pair of conductors and for successively connecting selected taps from said resistance to the third conductor, a further tapped resistance bridged across said pair of conductors, means at the central station for setting up code indicia comprising a plurality of electrically operated code indicia controlling devices severally bridged between different taps of said further resistance and third conductor, each code indicia controlling device being responsive to a potential established across it by the connection of said third conductor to a predetermined tap of each first mentioned resistance. 55

5. A fire alarm system comprising a plurality of heat responsive devices at different stations, a central station, three conductors common to all said devices and central station, a pair of said conductors being connected to the opposite terminals of a source of electromotive force, each device comprising a tapped resistance and 70

means responsive to heat for bridging said resistance across said pair of conductors and for successively connecting selected taps from said resistance to the third conductor, a further 5 tapped resistance bridged across said pair of conductors, means at the central station for setting up code indicia comprising a plurality of electrically operated code indicia controlling devices severally bridged between different taps 10 of said further resistance and third conductor, each code indicia controlling device being responsive to a potential established across it by the connection of said third conductor to a predetermined tap of each first mentioned 15 resistance.

6. In a signaling system, a central station, a plurality of devices at different stations each having movable means actuated in response to the condition to be signaled, a tapped resistance 20 associated with each of said devices, a source of electromotive force, switch means operated by said movable means of each of said devices for bridging said resistance associated with the device across said source of electromotive force 25 and for successively connecting selected taps from said resistance to a conductor common to all of said plurality of devices and the central station, a further tapped resistance bridged across said source of electromotive force, and 30 means at the central station for setting up code indicia comprising a plurality of electrically operated code indicia controlling devices severally bridged between said conductor and different taps on said further resistance.

7. In a signaling system, a central station, a plurality of devices at different stations each having movable means actuated in response to the condition to be signaled, a tapped resistance associated with each of said devices, a source of 40 electromotive force, switch means operated by said movable means of each of said devices for bridging said resistance associated with the device across said source of electromotive force, means operated in response to the heat generated by said resistance for successively connecting selected taps from said resistance to a conductor common to all of said plurality of devices and the central station, a further tapped resistance bridged across said source of 45 electromotive force, and means at the central station for setting up code indicia comprising a plurality of electrically operated code indicia controlling devices severally bridged between said conductor and different taps on said further resistances.

8. In a fire alarm system, a central station, a plurality of heat responsive means at different stations, a tapped resistance associated with each of said means, each resistance being tapped to divide a voltage impressed thereon in the same 50 way, a source of electromotive force, said means when responding to heat operating to bridge said resistance across said source of electromotive force, contact means operated by said heat responsive means for successively connecting a plurality of selected taps from said resistance to a conductor common to all of said plurality of heat responsive means and the central station, a further tapped resistance bridged across said source of electromotive force, which 55 resistance is tapped to divide the voltage of said source of electromotive force in substantially the same way as the first mentioned tapped resistances, and means at the central station for setting up code indicia comprising a plurality of electrically operated code indicia controlling de-

vices severally bridged between said conductor and different taps on said further resistance.

9. In a fire alarm system, a central station, a plurality of heat responsive means at different stations, a tapped resistance associated with each 5 of said means, each resistance being tapped to divide a voltage impressed thereon in the same way, a source of electromotive force, said means when responding to heat operating to bridge said resistance across said source of electromotive force, contact means operated in response to the current flowing through said resistance for successively connecting a plurality of selected taps from said resistance to a conductor common to all of said plurality of heat responsive means and the central station, a further tapped resistance bridged across said source of electromotive force, which resistance is tapped to divide the voltage of said source of electromotive force in substantially the same way as the first mentioned tapped resistances, and means at the central station for setting up code indicia comprising a plurality of electrically operated code indicia controlling devices severally bridged between said conductor and different 15 taps on said further resistance.

10. In a fire alarm system, a central station, a plurality of devices at different stations each having a like tapped resistance and thermostatic means for bridging said resistance across a source 30 of electromotive force and for successively connecting different selected taps from said resistance to a conductor, said conductor and a pair of other conductors, the latter leading from the terminals of said source of electromotive force 35 and adapted to have the several resistances of said devices so bridged across them, being common to all of said plurality of devices and the central station; a further tapped resistance bridged across said pair of conductors, means at 40 the central station for setting up code indicia comprising a plurality of electrically operated code indicia controlling devices severally bridged across said conductor and different taps on said further resistance, each tap of the first mentioned resistance when the latter is in circuit having a definite voltage relation to a tap on said further resistance, and said electrically operated code indicia controlling devices being severally operated when the voltage across them 45 is substantially such definite voltage relation established by the tap on said first mentioned resistance connected to said conductor.

11. A signaling apparatus comprising a plurality of devices at different stations responsive to 55 the conditions to be signaled, a central station, three conductors common to all of said plurality of devices and the central station, a pair of said conductors being connected to the opposite terminals of a source of electromotive force, each device comprising a tapped resistance and means for bridging said resistance across said pair of conductors and for successively connecting taps from said resistance to the third conductor, a further tapped resistance bridged across said 60 pair of conductors, means at the central station for setting up code indicia comprising a plurality of electrically operated code indicia controlling devices severally bridged between different taps of said further resistance and third conductor, said code indicia controlling devices being each responsive to a definite potential established across it by the connection of said third conductor to a definite tap of each of the first mentioned resistances, and means operating auto- 65

matically upon setting up of the code indicia by said controlling devices for causing the code indicia to be successively indicated.

12. In a signaling system, a plurality of devices at different stations responsive to the condition thereat to be signaled, a central station, a make and break switch at the central station, a plurality of groups of detents adapted to be set up in different combinations, a movable part 10 adapted to wipe over said detents for operating said make and break switch, electric means at the central station adapted to be operated by each of said devices for setting up said groups of detents in different combinations depending 15 upon the one of said devices which responds to said condition, a code signaling device at the central station controlled by said switch, a motor for operating said movable part, and means automatically operated upon the setting up of said 20 groups of detents in any one of said combinations for causing said motor to wipe said movable part over said detents.

13. In a signaling system, a plurality of devices at different stations responsive to the conditions thereat to be signaled, a central station, conductors common to all of said plurality of devices and the central station, all said devices having means for causing selected voltages to be 25 impressed successively on a certain one of said conductors when said device responds to the condition thereat to be signaled, a code indicia signal device at the central station, and means responsive respectively to the impression of said

voltages on said conductor for setting up respective code indicia of said signal device.

14. In a signaling system, a plurality of devices at different stations responsive to the conditions thereat to be signaled, a central station, conductors common to all of said plurality of devices and the central station, all said devices having means for causing selected voltages to be impressed successively on a certain one of said conductors when said device responds to the condition thereat to be signaled, a code indicia signal device at the central station, means responsive respectively to the impression of said voltages on said conductor for setting up respective code indicia of said signal device, and means operating 15 automatically upon the setting up of the code indicia for successively repeatedly indicating said code indicia set up.

15. In a signaling system, a plurality of potentiometer devices at different stations, a central station, three conductors common to all of said plurality of potentiometers and the central station, a pair of which conductors is adapted to energize the potentiometers, means at all of said potentiometers for selectively connecting any 25 one of them in circuit with said pair of conductors and for successively contacting selected points of the potentiometer to the third conductor, a code indicating signal device at the central station, and means responsive respectively 30 to the points of the potentiometer which are contacted for setting up respective code indicia of said signal device.

HAROLD J. GRAHAM.
